Inventor:
Paul F. Victor
By A. Miller Selfield,

UNITED STATES PATENT OFFICE

PAUL F. VICTOR, OF RIVER FOREST, ILLINOIS

AUTOMOBILE HEATER

Application filed May 15, 1929. Serial No. 363,145.

This invention relates to heating devices in general, and more particularly to heating devices adapted for use on automobiles.

It is highly desirable in connection with the manufacture and use of automobile heaters, that they be economical of manufacture and rugged and efficient in operation.

The primary object of this invention is accordingly to provide a heater adapted to 10 be used in automobiles, which may be economically manufactured and which is rugged and efficient in operation.

Another object of this invention is to provide a heater of the above type, the parts of 15 which may be conveniently assembled, which may be conveniently installed, and which is accessible for inspection, renewal, cleaning or repairing.

Other and further objects of this invention 20 will be apparent as the same becomes better understood from an examination of the specification and claims in connection with the accompanying drawings, wherein—

Fig. 1 is a fragmentary view, partly in 25 section, of an automobile provided with a heating system embodying this invention;

Fig. 2 is an enlarged fragmentary plan view of the heater;

Fig. 3 is a section taken on the line 3—3 30 of Fig. 2;

Fig. 4 is a section taken on the line 4—4 of Fig. 3;

Fig. 5 is a fragmentary side elevation of the heater;

Fig. 6 is an enlarged view, partly in section, of the valve mechanism for admitting the exhaust gases from the engine to the heater; and

Fig. 7 is an enlarged view, partly in section, of the means for operating the valve mechanism; and

Fig. 8 is a section taken at the line 8—8 of Fig. 2.

Referring to the drawings more particularly, reference character 8 designates the body of an automobile in the floor of the rear of which is secured a heater generally designated by the reference character 9. This heater is supplied by means of a pipe 11 connected through the intermediary of a valve

12 to the exhaust pipe 13 leading from the engine of the automobile. This valve 12 may be of any suitable type, but is preferably such as shown in Fig. 6 and comprises an elbow 14 in the form of a casting having an inlet 15 and an outlet 16. This casting 14 is strapped to the exhaust pipe 13 with its inlet 15 opposite an opening 16 formed in said pipe. A valve plate 17 resting upon a shoulder 18 formed integrally with the casting 14 in the inlet 15, is adapted to close said inlet and is secured upon a transverse shaft 19. This shaft 19 is provided outside of the casting 14 with an operating arm 21, which may be actuated to swing the plate 17 to open position, shown in dotted lines in Fig. 6, whereby exhaust gases from the engine may be admitted to the casing 14 and the pipe 11 leading to the heater. The front end of the pipe 11 is secured in the outlet 16 of the casing 14 by means of a set screw 22 provided with a locknut 23.

A link bar 24 hinged at its lower end to the arm 21 is flanged at its upper end and threaded to a rod 25. This rod 25 extends 75 through the floor of the automobile and is provided with a manually operable knob 26 in position to be conveniently operated by the driver for adjusting the valve plate 17 to open or closed position, or any intermediate 80 position depending upon the amount of heat desired. A threaded member 27 is also provided on the rod 25 and a spring 28 interposed between said member and a supporting plate 29 for the knob 26 imposes sufficient 85 pressure on said member 27 to cause sufficient resistance to the turning of said rod whereby the same will not move from adjusted position on account of the vibration of the automobile.

The heater 9 comprises an elongated annular member 31 outwardly flanged at its upper edge, as at 32, whereby it may be suspended from the floor of the automobile, and inwardly flanged as at 33 on its lower edge to retain the parts hereinafter described which constitute the heating element of the heater.

A shell 34 in the form of an inverted channel member closed at its ends forms a partition within the heater 9, the lower side of 100

which comes in contact with the exhaust gases from the engine and the upper side of which comes in contact with the air within the member 31. The lower side of the channel member or shell 34 is closed by a plate 35, a layer 36 of asbestos, or other heat insulation material, and a second plate 37. The plate 35 is provided with a plurality of longitudinally spaced upwardly struck aligned integral baffles 38^a and 38 and the plate 37 acts to reinforce said first plate. These baffles are provided with openings 39 for the passage of the exhaust gases which are admitted through an inlet opening 41 at one end of the heater and which are discharged through an outlet opening 42 at the other end of the heater. The baffles 38 are each provided with a recess 43 at their respective upper peripheries and extend in close proximity to the inner walls 20 of the shell 34 whereby a substantial proportion of the gases are caused to flow in relatively close proximity to the upper wall of said shell in the vicinity of said recess.

The opening 41 is provided with a threaded 25 deflector member 44 for receiving the pipe 11 and which extends through the plate 37 and the insulation material 36, and is provided with a hollow elbow or guide portion 40 which is situated in an aperture formed in 30 the plate 35 by the upwardly struck baffle 38^a and which extends above the plate 35 with its delivery end spaced just sufficient close to said baffle to allow the desired portion of the gases to escape between said end 35 and baffle and pass around the periphery of the baffle while the remainder of the gases pass through the opening 39. In this connection attention is invited to the fact that baffle 38^a is shaped differently from the baffles 38 40 in that the major portion of its periphery is spaced from the wall of the shell 34. In addition to apportioning the amount of gases desired to flow along the upper inner periphery of shell 34 and the amount desired to flow 45 through the openings 39, the member 44 acts to prevent erosion of the shell by the relatively highly heated gases admitted to the inlet of the heater. The baffle 38^a thus cooperates with the member 44 to restrict the 50 flow of gases into the shell and to distribute said flow thereby acting to some extent as both a safety valve or reducing valve and a distributing valve arrangement for the gases. A threaded member 45 without the 55 elbow or guide is provided in the opening 42 for an outlet pipe 46.

An upwardly dished cover 47 is hinged by means of hinges 48 to the top of the member 31 and forms an air chamber with the inner 60 walls of said member and the upper side of the shell 34. This air chamber is heated by radiation from the shell 34 and the heated air is adapted to circulate through openings 49 in the cover 47 to the interior of the automobile.

In manufacturing the heater, the plates 35 and 37 are assembled with the intervening layer 36 of insulation material and are secured in position with respect to the shell 34 by means of a bead or flange 51 formed along the edges of the latter. These parts 34 to 37, inclusive, are thus self-contained and may be conveniently attached to the member 31 by insertion from the top thereof and retained by beads 52, one on either side of said member for holding said parts against the flange 33. 70 75

The cover 47 being hinged to the heater body, access to the interior thereof may readily be obtained for inspection and cleaning, and even for removing the self-contained parts 35 to 37, inclusive, by merely springing the side walls of the member 31 outwardly to release said parts from the beads 52. 80

By causing a substantial proportion of the exhaust gases to flow through the recesses 43 in close proximity to the upper wall of the shell 34, which is relatively close to the top of the heater, increased efficiency thereof is obtained. 85

Other advantages will be apparent without further description. 90

I am aware that many changes may be made without departing from the principles of this invention, and I, therefore, do not 95 wish to be limited to the details shown or described.

What I claim is:

1. In a device of the class described, the combination of a shell forming an elongated 100 heating chamber, said chamber being provided with a gas inlet and a gas outlet, and a longitudinally extending plate provided with upwardly struck spaced baffles extending transversely of said chamber, the baffles 105 each provided with a recess at a predetermined position on its periphery and extending in close proximity to the walls of the chamber at either side of said recess to define a passage whereby a substantial proportion of the gases are caused to move in relatively close proximity to the wall of the chamber in the vicinity of the recess. 110

2. In a device of the class described, the combination of a shell forming an elongated 115 heating chamber, said chamber being provided with a gas inlet and a gas outlet, and a longitudinally extending plate provided with upwardly struck spaced baffles extending transversely of said chamber, the baffles 120 each provided with a recess at a predetermined position on its periphery and extending in close proximity to the walls of the chamber at either side of said recess to define a passage whereby a substantial proportion of the gases are caused to move in relatively close proximity to the wall of the chamber in the vicinity of the recess, said baffles being arranged with said recesses in alignment with each other. 125 130

3. In a device of the class described, the combination of a channel member and a base member for closing one side thereof and for forming a heating chamber with said channel member, said chamber being provided with a gas inlet and a gas outlet, and baffles therebetween, the edges of said channel member being formed to clamp said base member thereto.

4. In a device of the character described, the combination of a shell forming a heating chamber, said chamber being provided with a gas inlet and a gas outlet, means for delivering the major portion of the inlet gases toward the interior of the chamber away from the walls thereof, and means cooperating with said first means for causing a portion of the gases to flow toward the walls and for permitting a portion of the gases to flow along the axis of the chamber.

5. In a device of the character described, the combination of a shell forming a heating chamber, said chamber being provided with a gas inlet and a gas outlet, means for apportioning the delivery of some of the inlet gases toward the interior of the chamber away from the walls thereof and for causing a portion of said gases to flow toward the walls, and a plurality of apertured baffles extending transversely of the chamber between said means and outlet, the major portion of the periphery of said baffles extending in close proximity to the walls of the chamber and the remainder of the periphery permitting passage of the gases flowing along the walls of the chamber.

6. In a device of the class described, the combination of a shell forming a heating chamber, said chamber being provided with a gas inlet and a gas outlet, a guide member for the inlet gases communicating with said inlet and a baffle cooperating with said guide apertured to receive a restricted amount of gases therethrough and spaced sufficiently from the guide and the walls of the chamber for permitting a restricted flow of gases between said guide and baffle and around the periphery of the baffle.

7. In a device of the class described, an annular member, a heating member within said first member provided with a gas inlet and a gas outlet arranged for heating the air within the said first member; upwardly projecting flanges on the said heating member, inwardly projecting ridges in the said outer annular member, said flanges and said ridges cooperating to retain the heating member in position.

In witness whereof, I hereunto subscribe my name this 22nd day of April, A. D. 1929.

PAUL F. VICTOR.
